UNITED STATES PATENT OFFICE

ANTHONY J. STOUGES, OF QUEENS VILLAGE, NEW YORK, ASSIGNOR TO MERGENTHALER LINOTYPE COMPANY, A CORPORATION OF NEW YORK

MATRIX CABINET

Application filed June 19, 1931. Serial No. 545,381.

This invention relates to matrix cabinets, and more particularly to cabinets in which may be stored matrices differing in size and style, and adapted to be composed by hand in a suitable composing stick and to be used in casting large type for display purposes.

The different styles of matrices used for this type of work are the regular matrices, which are of standard height and which have ears projecting from their opposite edges, and a special earless matrix of greater than standard height. Because of the variable nature of the work involving their use, there are cases where a greater number of matrices of one style are required than of the other. Therefore, there is presented a difficult problem in the construction of a matrix cabinet adapted to accommodate the matrices required in the various kinds of composition, i.e., composition necessitating an equal number of regular and special matrices or composition requiring a greater number of one style of matrix than of the other, whether regular or special. An obvious manner in which to cope with the situation is to have a separate cabinet for each kind of matrices, and a choice of size in the cabinets, but this would involve too great an expense. Another apparent method is that of providing a cabinet with a majority of large drawers which could be used for holding both the special and the regular matrices. However, to do this would be not only to waste considerable space but it would render the withdrawal and replacement of the smaller regular matrices difficult because of the depth of the drawers.

It is, therefore, an object of the present invention to obviate these and other difficulties by providing a cabinet, which, from the standpoint of economy and efficiency, will more satisfactorily accommodate both regular and special matrices.

Another object of the invention is to provide means for holding a drawer in different partially withdrawn positions, and the association therewith of other means for automatically releasing such holding mechanism so that the drawer may be readily closed.

To these ends, the present invention, in its broader aspects, contemplates a cabinet construction such that large and small drawers may be used in the same cabinet, and may be substituted therein for one another. More specifically, the invention provides a cabinet having a plurality of drawers, at least one of which is of greater depth than the others, each drawer being supported on a pair of brackets, and the several pairs of brackets being arranged equidistant from one another so that one of the deeper drawers may be substituted for any two or more adjacent shallow drawers. The invention further provides a novel drawer-stop arrangement for holding a drawer in various partially withdrawn positions, and deflectors associated with the stops for automatically actuating the stops engaging latches in order that the drawer may be readily closed without manually disengaging the latches from the stops.

In the accompanying drawings the invention is shown merely by way of example and in preferred form, but obviously many modifications and variations may be made therein which will still be comprised within its spirit. It is to be understood, therefore, that the invention is not to be limited to any specific form or embodiment, except insofar as such limitations are specified in the appended claims.

In the accompanying drawings:

Fig. 1 is a vertical longitudinal section through the improved cabinet, partly broken away, and showing the front drawer, two single and one double drawer inserted;

Fig. 2 is a horizontal section taken on the line 2—2 of Fig. 1, looking in the direction of the arrows;

Fig. 3 is a front elevation of the cabinet, partly broken away to illustrate the interior at different levels;

Fig. 4 is a fragmentary vertical longitudinal section, illustrating the drawer guideway construction which permits the complete removal of the front drawer from the cabinet;

Fig. 5 is a plan view of a detached single drawer, illustrating means for holding regular matrices therein in a certain position;

Fig. 6 is a fragmentary vertical section taken on the line 6—6 of Fig. 5 looking in the direction of the arrows and more clearly illustrating the features shown therein;

5 Fig. 7 is a fragmentary view taken on the line 7—7 of Fig. 8 looking in the direction of the arrows, and illustrating the arrangement of the special matrices therein;

10 Fig. 8 is a plan view of a detached double drawer, illustrating a numerical and an alphabetical order of arranging the special matrices therein;

15 Fig. 9 is a fragmentary vertical section taken on the line 9—9 of Fig. 5 looking in the direction of the arrows, and showing the cooperation of the drawer-stop with the right rear upright drawer-bracket support;

20 Fig. 10 is a fragmentary vertical section taken on the line 10—10 of Fig. 9 looking in the direction of the arrows;

25 Fig. 11 is a plan view of the front drawer, partly broken away to show the association of the stop-latches with the improved stops and deflectors formed in the channeled guideways;

Fig. 12 is a rear view of the front drawer, showing the drawer-stop latch mechanism;

30 Fig. 13 is a perspective view of the complete cabinet, showing the different drawers partly withdrawn; and

Fig. 14 is a perspective view of a regular and a special matrix.

Referring to Fig. 13, the improved cabinet A shown therein is provided with an inclined 35 top a, bordered by slightly raised edges a¹, a², and a³, and is adapted to be used as a make-up table. When at work the composer stands at the front of the cabinet so it would be quite inconvenient to have all of the 40 drawers removable from this end. For this reason, the cabinet is constructed so that its drawers (with one exception) generally designated by the letter B, are insertable at one side of the cabinet, and are adapted to 45 slide transversely therein. These drawers are supported in the cabinet, see Fig. 1, each by a pair of angle-iron brackets D—D¹, secured at opposite sides of the cabinet to upright supporting pillars E—E¹. The brackets D—D¹ for each drawer lie in planes parallel to one another and parallel to the plane of the inclined top of the cabinet, and the several pairs of brackets are equidistant from one another. With this arrangement, a 55 space is left in the lower right-hand corner of the cabinet, and there is arranged in said space a drawer F, of any suitable size and shape, supported by the brackets f—f¹.

As shown in Fig. 14, the regular matrices 60 X differ considerably in size and shape from the new special matrices Y. However, since both styles of matrices are used in display work, it is convenient and desirable to keep them in the same cabinet, and in order to 65 store them most satisfactorily, there is pro-

vided by the present invention, see Fig. 1, a shallow drawer x for the regular matrices X, and a deeper drawer y for the special matrices Y. In both the shallow drawers x and the deeper drawers y, a number of longitudinal partitions x¹ and a number of transverse partitions y¹ divide the drawers into suitable compartments Z, the compartments being of the proper width to prevent the matrices from falling edgewise, and the inclined position of the drawers preventing them from being dislodged longitudinally of the compartment.

In Figs. 5 and 6 is illustrated a special type of drawer in which regular matrices, having ears projecting from their opposite edges, may be supported on edge, independent of the projecting ears and necessarily in similar positions. It is to be understood, however, that this type of drawer, although it may be used in the cabinet which is the subject of the present invention, forms no part thereof, it being fully described and claimed in a co-pending application, Serial No. 549,382.

The drawers x for holding the regular matrices X may be of the type shown in Fig. 5, to which reference has already been made, or they may be identical, except for depth, with the larger drawers y for holding special matrices Y, the latter drawers being twice as deep as the former or drawers x. As shown in Fig. 1, moreover, the larger drawers y are formed with their side walls grooved at their upper portions so that the same will clear the brackets when the drawers are in position in the cabinet. Since, also, as already stated, the pairs of supporting brackets D—D¹ are parallel and equidistant from one another, it is now readily apparent that a deeper drawer y, may be substituted at will for any two adjacent shallow drawers x. And so, with this construction, there is provided a cabinet which is adapted to support drawers for holding regular matrices, or in which those drawers can be replaced by deeper drawers which will accommodate special matrices; or, further, in which can be used a combination of the two different size drawers for storing both types of matrices.

Because these drawers are positioned in the cabinet on a transverse incline, they can be partially withdrawn any desired distance and yet not require stops to hold them. In order to prevent their complete withdrawal, however, there is provided at the rear of one side wall of each drawer a stop-latch P, see Figs. 5, 9, and 10, seated in a longitudinal groove Q and pivotally secured therein by the pin P¹. The latch P is adapted to engage the right rear upright support E² (see Figs. 5 and 10), being normally held in an outward engaging position by a compression spring p, seated in a recess p¹ in the side wall of the drawer. In order completely to remove the

drawer from the cabinet, it is necessary only to press the latch P inwardly against the pressure of the spring p , thereby permitting it to clear the upright supports E^2 , it being understood that the drawer has first been withdrawn a distance sufficient to permit access to said latch.

A drawer C , which is the top drawer of the cabinet, is located in the front thereof, and is slidable longitudinally therein, i. e., at right angles to the side drawers already alluded to. This front drawer C is divided by longitudinal and transverse partitions C^2 and C^3 , respectively, into compartments of suitable size, which are adapted to hold miscellaneous matrices, blanks, etc. According to one feature of the invention, it is slidably mounted, see Figs. 3 and 4, in a pair of channeled guideways $G-G^1$, each of which channels lies on one side and is secured to the top pair of supporting brackets $d-d^1$, and at regular intervals, see Fig. 11, each guideway $G-G^1$ is provided with a series of stops $g-g^1$, directly opposite one another and each having a deflector g^2 associated therewith.

At its middle, see Fig. 11, the drawer C is provided with a longitudinal bore K through which a rotatable rod H passes, the rear end of the rod being journaled in a bracket H^1 , secured to the rear wall of the drawer. A lever h^1 , see Fig. 12, is rigidly secured at its center to the portion of the rod H between the rear wall of the drawer and the bracket H^1 , and pivotally connected to the ends of the lever, as at h^2 , are latch rods h^3 . These latch rods extend laterally and project through the side walls c^1 of the drawer, and are normally held in a projecting position by a small tension spring h^4 , attached at one end to one of the latch rods and at its opposite end to the rear wall of the drawer. The projecting ends of the latch rods h^3 , see Fig. 11, are adapted to engage the stops $g-g^1$ of the channeled drawer guides $G-G^1$ to hold the drawer in different partially withdrawn positions, the rod H being operable through the lever h^1 to withdraw the latch rods h^3 from engagement with the stops $g-g^1$ in order that the drawer may be slid forward as desired. To permit the drawer to be readily closed, the deflectors g^2 , associated with the stops, serve to cam the projecting latch rods h^3 inwardly so that they will ride out of the recessed stops onto the channel walls, and thus the necessity for manually disengaging the latches from the stops is eliminated.

Secured to the inner faces of the side wall extension c^1 , see Figs. 4 and 11, are a pair of upwardly projecting drawer-stops c^2 , adapted to abut the front top cross member T of the cabinet to prevent the drawer from accidentally falling therefrom when withdrawn. In order that the drawer may be completely removed from the cabinet, however, the frame thereof below the drawer opening is

bent inwardly substantially at a right angle, as at L , instead of being formed to align with the ends of the bottom walls of the channel guideways $G-G^1$. Because of this construction of the cabinet frame, and due to the inclined position of the guideways, there is formed a recess l , of suitable conformation so that, when the forward end of the drawer is raised, the rear end thereof is permitted to tilt downward sufficiently for the stops c^1 to clear the front wall of the cabinet.

Having thus described my invention, what I claim is:

1. A matrix cabinet including in combination, a frame, a plurality of pairs of brackets supported by the frame and arranged equidistant from one another, a plurality of drawers arranged in the cabinet each supported by a pair of the brackets and adapted to occupy the space between the pair of brackets on which the drawer is supported and an adjacent pair of the brackets, and at least one drawer adapted to be supported by any pair of the brackets and to occupy a space greater than that between the pair of brackets on which the drawer is supported and an adjacent pair of the brackets.

2. A matrix cabinet including in combination, a frame, a plurality of pairs of brackets supported by the frame and arranged equidistant from one another, a plurality of drawers arranged in the cabinet each slidably supported by a pair of the brackets and adapted to occupy the space between the pair of brackets on which the drawer is supported and an adjacent pair of the brackets, and at least one drawer slidably supported by a pair of the brackets and adapted to occupy the space between three adjacent pairs of the brackets.

3. A combination as in claim 2, wherein the side walls of the last-mentioned drawer are formed so as to ride on the pair of brackets supporting the drawer and to clear the adjacent pair of brackets.

4. A combination as in claim 1, wherein the cabinet is formed with an inclined top and the several pairs of supporting brackets lie in planes parallel to the plane of the inclined top.

5. A combination as in claim 1, wherein the supporting brackets are arranged in the cabinet so as to support the drawers slidably transversely therein.

6. For a matrix cabinet having a frame, a drawer formed with a recess and a longitudinal groove in a side wall thereof, a compression spring located in the recess, a latch pivotally secured in the longitudinal groove and normally held in active position by said spring, said latch being adapted to engage the frame of the cabinet to prevent accidental complete withdrawal of the drawer therefrom.

7. A matrix cabinet including in combina-

tion, a frame, a drawer, means arranged on the frame and adapted slidably to support the drawer therein, and a locking device arranged to hold the drawer in selective position

5 in said supporting means, said device including as one element a series of stops, and as another element a device for selectively engaging the stops, one of said last two elements being arranged on the drawer and the 10 other of said elements being arranged on the supporting means.

8. A matrix cabinet including in combination, a frame, channeled guides arranged on the frame and adapted slidably to support a 15 drawer therein, a series of stops arranged on the guides, and a device on the drawer adapted selectively to engage the stops.

9. A matrix cabinet including in combination, a frame, channeled guides arranged on the frame and adapted slidably to support a 20 drawer therein, a series of stops arranged on the guides, a device on the drawer adapted selectively to engage the stops as the drawer is moved forwardly, and means associated 25 with the stops for rendering said device inactive when the drawer is moved rearwardly.

10. A matrix cabinet including in combination, a frame, channeled guides arranged on the frame and adapted slidably to support 30 a drawer therein; stops arranged directly opposite one another and at spaced intervals on the guides, a latch mechanism including a plurality of latch rods adapted selectively to engage the stops, and a control operable 35 from the front of the drawer to disengage the latch rods from the stops.

11. A matrix cabinet including in combination, a frame, channeled guides arranged on the frame and adapted slidably to support 40 a drawer therein, stops arranged in registry and at spaced intervals on opposite guides, a latch mechanism including two oppositely extending latch rods adapted selectively to engage the stops, a control extending thru 45 the drawer and operable from the front thereof to disengage the latch rods from the stops and permit the drawer to be moved forwardly and deflectors associated with the stops and adapted automatically to render 50 the latch mechanism inactive when the drawer is moved rearwardly.

12. A combination as in claim 11, wherein 55 stops are also arranged at the rear of the drawer and are adapted to engage a cross member of the frame to prevent the drawer from accidental complete withdrawal from the cabinet.

13. A combination as in claim 11, wherein 60 stops are also arranged at the rear of the drawer and adapted to engage a cross member of the frame to prevent the drawer from accidental complete withdrawal from the cabinet, the construction of the frame and the forward ends of the channeled guides being such that the front end of the drawer may

be raised to tilt the rear end thereof downward sufficiently for said stops to clear the cross member in order that the drawer may be completely removed from the cabinet.

14. For a matrix cabinet, a drawer comprising a bottom, front and rear walls, and side walls, a hollow partition extending longitudinally of the drawer, a latch mechanism arranged at the rear of the drawer, and means located in said hollow partition and 75 operable from the front of the drawer to actuate the latch mechanism.

15. For a matrix cabinet, a drawer comprising a bottom, front and rear walls, and side walls, a bracket secured to the outer face 80 of the rear wall, a partition in the drawer extending between the front and rear walls and formed with a longitudinal bore, a rod extending rearwardly from the front of the drawer thru said bore and being journaled 85 in said bracket, and a latch mechanism mounted on the rod at the rear of the drawer, said rod being operable at the front of the drawer to actuate the latch mechanism.

16. A matrix cabinet drawer comprising 90 a bottom, front and rear walls, and side walls extending rearwardly beyond said rear walls, a rotatable rod extending rearwardly thru the front and rear walls, a bracket secured to the outer face of the rear wall and in which 95 one end of the rod is journaled, a lever rigidly mounted at its center on the portion of the rod between the rear wall of the drawer and the bracket, a pair of latch rods pivotally secured one at the end of each arm 100 of the lever and projecting laterally thru the side wall extensions, a tension spring secured at one end to one of the latch rods and at the other end to the rear wall of the drawer and arranged normally to hold the latch 105 rods in projecting position, the projecting latch rods being manually retractable by means of the rotatable rod operable from the front of the drawer.

17. A matrix cabinet including in combination, a frame, a plurality of pairs of brackets arranged equidistant from one another on the frame and adapted to support a plurality of drawers slideable transversely of the cabinet, drawer-supporting guides secured to the top pair of said brackets and adapted to support a drawer slideable at right angles to said other drawers, and cooperating means on said supporting guides and drawer to maintain the latter in partially withdrawn 115 positions.

18. A matrix cabinet including in combination, a frame, a plurality of pairs of brackets arranged equidistant from one another on the frame and adapted to support a plurality of drawers slideable transversely of the cabinet, and a pair of channeled guides secured to the top pair of said brackets and adapted to support a drawer slideable at right angles to said other drawers, the channeled 125 130

guides being formed with a series of stops adapted to be selectively engaged by a latch mechanism on the drawer whereby the drawer may be held in partially withdrawn positions.

19. A combination as in claim 17, characterized by the fact that the cabinet is provided with an inclined top adapted to be used as a make-up table and wherein the pairs of 10 drawer-supporting brackets and the supporting guides lie in planes parallel to the plane of the inclined top.

In testimony whereof, this specification has been duly signed by:

15 ANTHONY J. STOUGES.
